UNITED STATES PATENT OFFICE.

HARRY W. BARNES, OF BRISTOL, CONNECTICUT.

GONG-BELL.

SPECIFICATION forming part of Letters Patent No. 286,169, dated October 9, 1882.

Application filed August 15, 1883. (Model.)

To all whom it may concern:

Be it known that I, HARRY W. BARNES, of Bristol, in the county of Hartford and State of Connecticut, have invented certain new and useful Improvements in Gong-Bells; and I do hereby declare the following to be a full, clear, and exact description of the invention, such as will enable others skilled in the art to which it appertains to make and use the same.

My invention relates to an improvement in clock-bells, and more particularly to that class thereof known as "cathedral gong-bells," the objects of the invention being to provide an improved standard for supporting the bell and attaching it to the clock-case, to adapt the several parts of the bell to be united and to be attached to the standard by a single screw, and to provide an improved collet for the gong.

20 A further object of the invention is to produce a bell which shall require the minimum amount of space in the clock-case.

With these objects in view my invention consists in certain details of construction and 25 combinations of parts, as will be hereinafter described, and pointed out in the claim.

In the accompanying drawings, Figure 1 is a plan view of a gong constructed in accordance with my invention. Fig. 2 is a view 30 thereof in vertical section, and Fig. 3 is a detailed view of the standard.

The standard consists of three perforated arms, A, and a connecting-arm, B, the same being cast in one piece. The arms A receive 35 the screws by which the bell is secured to the clock-case, while the arm B forms the connection between the standard and the head. The said arm B, which stands out from the arms A, is provided with an enlarged end, E, 40 having a smooth outer face, and pierced by a screw-threaded perforation, F, the same being adapted to receive the end of the screw G, by which the several parts of the bell are secured together and attached to the stand- 45 ard. It is to be observed at this point that in order to obtain the best results from this type of bell it is necessary that the connection between the standard and sounding-head must be such as will allow the latter to vibrate 50 responsive with the gong itself.

The sounding-head C, which is preferably made of cast-iron, has a recess, H, formed in its inner face, its outer face being flat. It is also provided with a central perforation, I, which receives the screw G, aforesaid. A 55 sounding-head constructed as described has the advantage of being cheap, being composed of iron, and, moreover, it is of a shape which is easily and perfectly cast. By providing the sounding-head with the recess H it is adapted 60 to receive the standard, and thereby reduce the space occupied by the bell and standard to the minimum.

The scalp J, which is employed to cover the sounding-head, and thus impart a finish to 65 the bell, is preferably formed of stamped sheet-brass. Like the sounding-head, it is provided with a central aperture, K, to receive the screw G. I would have it understood that the scalp is not an indispensable feature of 70 my improved bell, for it may be omitted, if desired. It may, for instance, be omitted when the construction of the clock-case and the position of the bell therein completely conceals the same; or it may be dispensed with and 75 the sounding-head left plain or suitably ornamented.

The inner end of the volute gong D is welded, brazed, soldered, or otherwise secured to a small brass collet, L, the latter having the 80 bearing-faces, either or both, beveled, as at N. The end of the gong is secured to the thickest edge of the collet, wherefore, when the beveled face is seated upon the scalp, or upon the flat outer surface of the sounding-head, the 85 gong will be raised, as shown, to the desired elevation above the scalp or head. By beveling the collets as described I am enabled to employ smaller collets than have heretofore been available for this purpose. The gongs 90 also are held out of possibility of contact with the scalp or sounder during their vibration.

It is apparent that my improvement is susceptible of some changes and alterations. I would therefore have it understood that I do 95 not limit myself to the exact construction and arrangements of parts herein shown and described, but hold myself at liberty to make such variations as legitimately fall within the spirit and scope of my invention.

Having fully described my invention, what I claim as new, and desire to secure by Letters Patent, is—

In a gong-bell, the combination, with a stand and adapted to be attached to a clock-case and provided with a perforated connecting-arm, of an independent perforated sounding-head, a volute gong attached to a perforated collet, and a single screw securing the collet and

sounding-head to the connecting-arm of the stand, substantially as described.

In testimony whereof I have signed this specification in the presence of two subscribing witnesses.

HARRY W. BARNES.
